US00D561877S

(12) **United States Design Patent** (10) **Patent No.:** **US D561,877 S**
Hopkins et al. (45) **Date of Patent:** **** Feb. 12, 2008**

(54) **SEAL CARRIER FOR
ULTRAHIGH-PRESSURE FLUID SYSTEMS**

(75) Inventors: **Jordan J. Hopkins**, Seattle, WA (US);
Adrian Hawes, Seattle, WA (US)

(73) Assignee: **Flow International Corporation**, Kent,
WA (US)

(**) Term: **14 Years**

(21) Appl. No.: **29/250,411**

(22) Filed: **Nov. 13, 2006**

Related U.S. Application Data

(63) Continuation-in-part of application No. 10/423,661, filed on Apr. 25, 2003, now Pat. No. 7,247,006, which is a continuation-in-part of application No. 10/038, 507, filed on Jan. 2, 2002, now Pat. No. 6,802,541.

(57) **CLAIM**

The ornamental design for a seal carrier for ultrahigh-pressure fluid systems, as shown and described.

DESCRIPTION

FIG. 1 is a top perspective view of a seal carrier for ultrahigh-pressure fluid systems, showing our new design.

FIG. 2 is a bottom plan view thereof.

FIG. 3 is a left side elevational view thereof, front and rear elevational views being identical.

FIG. 4 is a right side elevational view thereof; and,

FIG. 5 is a top plan view thereof.

The broken lines in the figures are for illustrative purposes only and form no part of the claimed design.
